[57] CLAIM

The ornamental design for a rod guide gauge, as shown and described.

DESCRIPTION

FIG. 1 is a back view of a rod guide gauge according to the present invention;

FIG. 2 is a front view of the rod guide gauge as shown in FIG. 1;

FIG. 3 is a left end view of the rod guide gauge as shown in FIG. 2;

FIG. 4 is a right end view of the rod guide gauge as shown in FIG. 2;

FIG. 5 is a top view of the rod guide gauge as shown in FIG. 2;

FIG. 6 is a bottom view of the rod guide gauge as shown in FIG. 2;

FIG. 7 is a back view of another embodiment of a rod guide gauge according to the invention;

FIG. 8 is a front view of the rod guide gauge as shown in FIG. 7;

FIG. 9 is a left end view of the rod guide gauge as shown in FIG. 8;

FIG. 10 is a right end view of the rod guide gauge as shown in FIG. 8;

FIG. 11 is a top view of the rod guide gauge as shown in FIG. 8;

FIG. 12 is a bottom view of the rod guide gauge as shown in FIG. 8;

FIG. 13 is a back view of another embodiment of a rod guide gauge according to the invention;

FIG. 14 is a front view of the rod guide gauge as shown in FIG. 13;

FIG. 15 is a left end view of the rod guide gauge as shown in FIG. 14;

FIG. 16 is a right end view of the rod guide gauge as shown in FIG. 14;

FIG. 17 is a top view of the rod guide gauge as shown in FIG. 14;

FIG. 18 is a bottom view of the rod guide gauge as shown in FIG. 14;

FIG. 19 is a back view of a rod guide gauge according to the present invention;

FIG. 20 is a front view of the rod guide gauge as shown in FIG. 19;

FIG. 21 is a top view of the rod guide gauge as shown in FIG. 20;

FIG. 22 is a bottom view of the rod guide gauge as shown in FIG. 20;

FIG. 23 is a left side view of the rod guide gauge as shown in FIG. 20; and,

FIG. 24 is a right side view of the rod guide gauge as shown in FIG. 20.

The broken line showing of a ring and rod guide gauges are for illustrative purposes only and forms no part of the claimed design.
